CLAIM

The ornamental design for a pegboard, as shown and described.

DESCRIPTION

FIG. 1 is a front, right, top perspective view of a pegboard, showing my new design;

FIG. 2 is a rear, left, bottom perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof;

FIG. 7 is a bottom plan view thereof;

FIG. 8 is front, right, top perspective view of the pegboard in a detached state;

FIG. 9 is a rear, left, bottom perspective view of the pegboard in a detached state; and,

FIG. 10 is an enlarged view of detail 10 in FIG. 9.

The dashed broken lines in the figures illustrate portions of the pegboard that form no part of the claimed design.

The dash-dot-dash broken lines are for notating enlarged views and form no part of the claimed design.
